UNITED STATES PATENT OFFICE.

NELS A. JENSEN, OF WILLMAR, MINNESOTA.

FLAGSTAFF.

1,102,413.

Specification of Letters Patent. Patented July 7, 1914.

Application filed November 13, 1913. Serial No. 800,711.

To all whom it may concern:

Be it known that I, NELS A. JENSEN, a citizen of the United States, residing at Willmar, in the county of Kandiyohi and State of Minnesota, have invented certain new and useful Improvements in Flagstaffs; and I do hereby declare the following to be a full, clear, and exact description of the invention, such as will enable others skilled 10 in the art to which it appertains to make and use the same.

My invention relates to improvements in flagstaffs, and, to this end, it consists of the novel devices and combinations of devices 15 hereinafter described and defined in the claim.

In the accompanying drawings, which illustrate the invention, like characters indicate like parts throughout the several 20 views.

Referring to the drawings, Figure 1 is a side elevation of the improved flagstaff, some parts being broken away, some of the exposed parts being sectioned, and some parts 25 being shown in different positions by dotted lines; and Fig. 2 is a longitudinal vertical section taken on the line $x^2 x^2$ of Fig. 1.

The numeral 1 indicates a flagstaff constructed from metallic pipe sections decreasing successively in diameters from the base 30 of the flagstaff up. These pipe sections are connected by couplings 2, having upper and lower studs 3 of different diameters, onto which the adjacent ends of said sections are 35 telescoped. The pipe sections are shrunk onto the studs 3 in the well-known manner, and said studs are secured to the couplings 2 by screwthreaded engagement. Journalized in a bracket secured to the top of the flag- 40 staff, just below the ball thereof, is a sheave 4 to which the halyard, not shown, is secured.

The flagstaff 1 is intermediately fulcrumed to the top of a tubular standard 5, secured 45 in an upright position by setting the lower end thereof in the ground and tamping the dirt therearound, or setting the same in cement. In case the improved flagstaff is placed on a building, the standard 5 will be 50 provided with a suitable base flange bolted or otherwise secured to the building.

A bifurcated head 6, to which the flagstaff 1 is fulcrumed, is secured to the top of the standard 5 by a stud 7. The lower end of the stud 7 is telescoped into the standard 5 55 and secured thereto by shrinking the standard thereon, and the upper end of said stud has screw-threaded engagement with the head 6. The prongs 8 of the head 6 are bent laterally and extend to one side of the standard 5. In the upper horizontal edges of the prongs 8 are formed open seats 9. The prongs 8 are adapted to embrace the flagstaff 1, and the lower coupling 2 is provided with a pair of radially projecting trunnions 65 10 loosely journaled in the seats 9.

As best shown in Fig. 1, the flagstaff 1, when in an upright position, extends parallel with the standard 5, and is secured in this position by a nut-equipped bolt 11 70 passed through the standard 5 and the lower end of the flagstaff 1. From the above description, it is evident that the flagstaff 1 is free to swing from an upright position into a horizontal position. The engagement of 75 the lower end of the flagstaff with the standard 5 acts as a stop and prevents the flagstaff from moving more than ninety degrees.

A flagstaff constructed in accordance with my invention may be lowered from time to 80 time, for the purpose of painting the same, or to replace the halyard.

What I claim is:—
The combination with a support having a pair of horizontal laterally spaced prongs 85 extending to one side thereof, of a flagstaff intermediately fulcrumed to said prongs for swinging movement to and from a vertical position in a plane which includes the axis of said support, said flagstaff when in a 90 vertical position extending parallel to said support, and means for locking the lower end of said flagstaff, when in a vertical position, to said support.

In testimony whereof I affix my signature 95 in presence of two witnesses.

NELS A. JENSEN.
